[57] CLAIM

The ornamental design for desk top two-way radio
control unit or similar article, as shown and described.

DESCRIPTION

FIG. 1 is a front, top and right side perspective view of
a desk top two-way radio control unit or similar article
showing my new design;

FIG. 2 is a left side elevational view thereof;

FIG. 3 is a rear elevational view thereof;

FIG. 4 is a bottom plan view thereof;

FIG. 5 is a front, top and right side perspective view of
a second embodiment of the control unit illustrated in
FIG. 1.

The broken line showing of the handset in FIG. 1 and
the Microphone in FIG. 5 is for illustrative purposes
only and forms no part of the claimed design.

FIG. 1

FIG. 2

FIG. 3

FIG. 4
